DOOR CLOSING DEVICE

Filed Jan. 25, 1922.

BY

INVENTOR

J. Hauenstein

ATTORNEY

UNITED STATES PATENT OFFICE.

JULIUS HAUENSTEIN, OF JERSEY CITY, NEW JERSEY.

DOOR-CLOSING DEVICE.

Application filed January 25, 1922. Serial No. 531,636.

To all whom it may concern:

Be it known that I, JULIUS HAUENSTEIN, a citizen of the United States, residing at Jersey City, in the county of Hudson and State of New Jersey, have invented certain new and useful Improvements in Door-Closing Devices, of which the following is a specification.

This invention relates to improvements in door closing devices, one of its objects being to provide means attached to the lower end of a door, to allow the latter after being swung open, to return to its original closed position, without any further effort or attention.

A further object is to provide a device adapted to replace the usual type of hinges in general use at the present time, and which use a spring for closing the door after it has been opened. These spring hinges have become objectionable on account of frequent replacements required, owing to breaking or loss of tension.

These and other objects will become apparent in the description below in which similar characters of reference refer to like-named parts in the drawing.

Referring briefly to the drawing, Figure 1, is a front elevational view of a door and its frame as used on ice boxes or the like, the self closing device being shown in place at the lower hinge end.

Figure 2 is a sectional view taken on line 2-2 of Figure 1.

Figure 3 is perspective view of the roller carrying frame.

Figure 4 is a perspective view of the lifter cam block.

Describing the drawing more in detail, numeral 1 indicates a relatively heavy door of an ice box, which when closed, fits snugly into the outwardly tapered opening of the wall. The construction mentioned is usual, the purpose being to prevent the air within the ice box from reducing the temperature, by escaping thru the crevices formed between the door and wall. The door is carried on special hinges comprising fixed pivot plates 3 which are secured to the upright frame member 4. These plates have spaced ears 5 extending outwardly therefrom and are adapted to receive hinge bars 6. Bolts 7 fixed in the ears form pivots upon which the door is supported, the ends being secured between ears 7 extending from

plates 8, permanently secured to the door 1 in horizontal alignment with the pivot plates.

Yoke members 10 located centrally on the length of hinge bars 6 form guides and additional means for supporting the door and preventing the same from sagging and thus twisting the pivot plates from the door or frame. It is obvious that mounting the door upon hinges such as are shown will permit the door to fit snugly into the door opening. Flat curved leaf springs 9, secured between the door surface and hinge bars 6 in the region of guide yokes 10, urge the door away from the hinge bars and into more intimate contact with the opening, thus insuring a snug fit at all times.

The self closing device, essentially composed of a channelled frame 11, is preferably secured in an upright position to the lower hinge bar by suitable bolts 12 by passing thru holes 12'. Slits 13 cut thru the side webs of the channelled frame form means for supporting the device when being lifted. An angle iron 14 and an anchor brace 14', extending angularly downward, form means for securing the closing device to the lower door hinge. A pair of plates 15 secured to the interior surface of the frame webs at the lower end of the frame 10 by bolts 15', have small lugs 16 which shoulder upon the lower edge of the said frame. A roller 17 is rotatably mounted between plates 15 upon a suitable spindle retained in position between the frame webs. The roller 17 is so located as to have its periphery project somewhat below the side plates 15, and engages to ride upon an inclined arcuate cam track 18, formed upon a rigid metallic block 19 secured to the floor in an approved manner so that the roller 17 will, when the door is closed, be riding upon the shallow part of the cam track 18 as indicated by numeral 20, and when the door is being opened, will ride upward upon the arcuate path until the roller meets the stop lug 21 which provides means for limiting the opening of the door. Obviously, the door when being opened will be lifted a distance equal to the perpendicular height of the cam track 18. For this reason the upper ears 5 of the hinge plates 3 are spaced sufficiently apart to permit this upward movement of the door as the same is being swung open.

When opening the door a common type of spring bolt 22 is drawn from the keeper 23, and the door pulled open to the position desired. In opening, the door will follow the course of cam track 18, the latter being of such angle as to overcome any frictional resistance of the hinges and other members which might hold the door open at any position. Therefore as soon as retaining pressure is released, the roller will slowly begin descending the track, gaining momentum due to the weight of the door which is closed thereby.

I claim:

15 The combination with a door and its frame, of a closing device comprising a pair of hinge bars secured to the door, hinge plates secured to the frame, a pair of spaced horizontal ears extending from the frame 20 plates, a vertical pin rigidly supported to extend between each pair of ears, the outer extremities of said bars extending beyond

the door and being rotatably supported by said pins as axes, said hinge bars being adapted to rise and fall on said pins between each pair of ears during opening and closing, of the door, a channelled frame secured in vertical position to the lower hinge bar, a roller axially mounted at the lower end of said frame between the sides thereof and extending below the lower extremities of said frame, and an arcuate inclined cam track secured to the floor beneath the roller, said roller being adapted to engage the lower end of the cam track when closed and to ride upward on said track during opening of the door, the weight of the door causing said roller to descend said track when the opening force on the door has been released, to cause said door to close.

In witness whereof I affix my signature.

JULIUS HAUENSTEIN.
